Primary Examiner — Susan Moon Lee(74) *Attorney, Agent, or Firm* — Heslin Rothenberg Farley & Mesiti P.C.(57) **CLAIM**

The ornamental design for swimming goggles, as shown and described.

DESCRIPTION

FIG. 1 is a perspective view of the swimming goggles of the present invention;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; the left side elevation view being a mirror image thereof;

FIG. 7 is an enlarged section view thereof taken along line A-A of FIG. 5;

FIG. 8 is an enlarged section view thereof taken along line B-B of FIG. 5;

FIG. 9 is an enlarged section view thereof taken along line C-C of FIG. 5; and,

FIG. 10 is an enlarged section view thereof taken along line D-D of FIG. 6.

The cushion member of the swimming goggles is provided with ornamental undulating surface. The lines on the surface denote respective ridge lines.

The broken line showing represents environmental structure and forms no part of the claimed design.
